R. T. MILLER.

FLUE OR TUBE CUTTER.

UNITED STATES PATENT OFFICE.

RAY T. MILLER, OF DEFIANCE, OHIO.

FLUE OR TUBE CUTTER.

SPECIFICATION forming part of Letters Patent No. 787,205, dated April 11, 1905.

Application filed March 10, 1904. Serial No. 197,400.

To all whom it may concern:

Be it known that I, RAY T. MILLER, a citizen of the United States, and a resident of Defiance, in the county of Defiance and State of Ohio, have invented a new and Improved Flue or Tube Cutter, of which the following is a full, clear, and exact description.

This invention relates to rotary flue or tube cutters; and it consists, substantially, in the construction and combinations of parts hereinafter particularly described, and pointed out in the claims.

One of the principal objects of the invention is to overcome numerous disadvantages and objections common to many other structures hitherto devised with like ends in view and to provide a device of this kind which is simple and comparatively inexpensive to manufacture, besides being easily and quickly ap-

plied and adjusted and readily manipulated. A further object is to provide a device of the character referred to which is thoroughly effective and reliable in operation and which also possesses the capacity for long and repeat-

ed service.

The above and additional objects are attained by means substantially such as are illustrated in the accompanying drawings, forming a part of this specification, in which similar characters of reference indicate corresponding parts in all the figures.

Figure 1 is a side view of a rotary flue or tube cutter embodying my improvements, the operating-handle therefor being partly broken off. Fig. 2 is a longitudinal sectional view of the same. Fig. 3 is an enlarged transverse sectional view on the line 3-3 of Fig. 1 looking in the direction of the arrows. Fig. 4 is an enlarged view in elevation, with a part of the structure removed, on the line 4-4 of Fig. 1 and looking in the direction of the arrows at such line. Fig. 5 is an enlarged side view of the operating-head for the laterally-adjustable cutter-blocks, the stem of the head being partly broken off; and Fig. 6 is a view of the inner face of one of the cutter-blocks.

Before proceeding with a more detailed description it may be stated that in the form of my improvements herein shown I employ a hollow body or stock of special construction

in which works an adjustable stem, having at one end thereof a specially-constructed head. A set of laterally-movable blocks is co-operatively organized with the body and head, each being also of special construction and provided with a cutter, while mounted upon the body is a set of devices for rotating the structure in the operation thereof. A solid longitudinal extension is employed at one end of the body, having thereon a pilot for supporting the structure within a flue or tube to be cut, and while I have herein represented my improvements in a certain preferred embodiment it will be understood, of course, that I am not limited to the precise details thereof in practice, since immaterial changes therein may be resorted to coming within the scope of my invention.

Specific reference being had to the accompanying drawings by the designating characters marked thereon, 1 represents the body, or stock of the device, the same being hollow for its entire length and preferably reduced in external diameter for a suitable distance from one end, so as to form a slender section 2 and an annular shoulder 3. At diametrically opposite sides of the other end thereof the said body is formed with substantially duplicate notches 4 of suitable depth, which extend inwardly and are in communication with a recess 5, formed by reducing the thickness of opposite portions of the body at 6 for a suitable distance, the inner terminal of the bore 8 of the body leading substantially from the center of the base of said recess, as shown in Fig. 2. Working in said bore is a longitudinally-movable stem 9, having at one end a head 10, which is wedge-shaped or beveled outwardly at the opposite edges 11 thereof, one flat face, 12, of said head being provided at one of said edges with a raised flange 13 and the opposite flat face, 15, thereof with a similar flange 16 at the other edge, and working in opposite directions through said notches 4 at right angles to the head and its stem are duplicate substantially oblong blocks 17, disposed on the opposite faces of the head, each block being formed in its inner face with a diagonal groove 18, receiving between the sides thereof the corresponding flange 13 or 16 of the

head, a rotary cutter 19 being mounted in each block, so as to project beyond the outer end thereof, as shown. Fitted to the notched end of the body 1 by means of a screw 20 is 5 the inner enlarged end 21 of a solid extension 22 of the body, the outer end of said extension being preferably reduced at 23 and received in a central opening therefor in a pilot 24, having radial branches 25 provided with 10 suitable headed screws 26, which may be adjusted in proper degree, so as to secure the structure in place within a flue or tube to be operated upon, said pilot being held upon said reduced end of the extension, preferably 15 by means of a disk 27 and screw 28.

The stem 9 is reduced in diameter for a suitable distance from the end thereof opposite to the head 10, as indicated at 28^a, so as to form an annular shoulder 29, this portion of 20 said stem being threaded at 30 for the reception of jam-nuts 31 and 32, which, in conjunction with a washer 33, securely hold against said shoulder 29 the inner end of a sleeve 34, which turns on said reduced portion 28^a of 25 the stem and is threaded externally at 35 to engage a corresponding thread formed internally of the slender section 2 of the body, the outer end of the sleeve having a squared head 34^a. Secured rigidly upon this section at 36 is a 30 ring 37, having ratchet-teeth 38 on its outer surface, and rotatably mounted upon said section is a yoke 39, which embraces the sides of said ring and abuts against the annular shoulder 3 of the body and is held in position by 35 means of a collar 40 and a screw 41. The said yoke is provided with a spring-pressed pawl 42, coöperating with the ratchet-teeth 38, and is also provided with a handle 43, and it will be seen that on turning the yoke in one direction 40 the said pawl will glide over the ratchet-teeth, while one of the latter will be engaged by the pawl on turning the yoke in the opposite direction, thus to turn practically the entire structure for effecting the desired cutting 45 of a flue or tube. To move the cutter-blocks in or out, it is simply necessary to apply a wrench to the squared head 34^a of the sleeve 34 and then turn in the proper direction and tighten the jam-nuts, whereupon the head 50 and cutter-blocks will be held to the work to be accomplished by abutment of the inner end of said sleeve against the annular shoulder of the stem.

It is thought the construction and operation 55 of my improved device will be fully understood without further elucidation, although it may be added that at the outer end thereof each cutter-block is provided with a thickened portion 44, beveled for a part of its inner 60 edge at 45 to move against the adjacent outer side of the head 10, and each block is formed in its inner face with a longitudinal groove 46, intersecting at its inner end with a diagonal groove of the block and receiving the 65 adjacent projecting portion of the rotary cut-

ter of the other block, thus permitting both blocks to work substantially flatly upon the faces of the head. In order to accommodate the head in the forward movements imparted thereto for effecting the outward adjustments 70 of the blocks, the face of the enlarged inner end 21 of the body extension 22 is recessed for a suitable depth, as indicated at 47.

Having thus described my invention, I claim as new and desire to secure by Letters Patent— 75

1. A flue or tube cutter, comprising a hollow body, a stem longitudinally adjustable in the body and provided at one end with a flat wedge-shaped head having a flange at one edge of one of its faces and a similar flange 80 at the opposite edge of its other face, and cutter-blocks having enlarged outer ends and lying on the opposite faces of the wedge-shaped head with the inner end of one in engagement with the enlarged outer end of the other, 85 said blocks being provided on their inner faces with diagonal grooves to receive the flanges of the said head.

2. A flue or tube cutter, comprising a hollow body, a stem longitudinally adjustable in 90 the body and provided with a wedge-shaped head having a flange at one edge of one of its faces and a similar flange at the opposite edge of its other face, rotary cutters, and blocks carrying said cutters, said blocks having enlarged outer ends and lying on opposite side faces of the wedge-shaped head with the inner end of one in engagement with the enlarged outer end of the other, the blocks being provided on their inner faces with diagonal 95 grooves to receive the flanges of the head and with longitudinal grooves intersecting the diagonal grooves to receive the projecting portions of the rotary cutters.

3. A flue or tube cutter, comprising a hollow body having an internally-threaded portion at one end, a stem longitudinally adjustable in the body and provided with a wedge-shaped head at one end and having its other end reduced and threaded for a portion of its 105 length, a headed and threaded sleeve on the reduced portion of the stem and screwing into the body, nuts on the stem beyond the head of the sleeve, cutter-blocks on opposite sides of the head, and working in opposite directions through the body, a sleeve on the reduced end of the stem and threaded to engage the threaded portion of the body, and a ratchet-and-pawl mechanism mounted on the body. 110

4. A flue or tube cutter, comprising a hollow body reduced in external diameter from one end to form a slender section and an annular shoulder, said section being internally threaded, a stem longitudinally adjustable in the body and provided at one end with a 115 wedge-shaped head, and at the other end with a reduced portion and an annular shoulder, said portion being threaded for a part of its length and provided with jam-nuts, duplicate cutter-blocks disposed across the opposite 120

125

130

faces of the head and working in opposite directions through the body, an adjusting-sleeve upon said reduced portion of the stem, threaded to engage said slender section of the body, 5 and a ratchet-and-pawl device for rotating the structure, the same being mounted upon the section and abutting against said annular shoulder of the body.

In witness whereof I have signed my name to this specification in the presence of two subscribing witnesses. 10
